UNITED STATES PATENT OFFICE.

JOHN WALDHEIM, OF ELIZABETH, NEW JERSEY, ASSIGNOR TO UNDERWOOD ELLIOTT FISHER COMPANY, OF NEW YORK, N. Y., A CORPORATION OF DELAWARE.

TYPEWRITING MACHINE.

Application filed September 13, 1924. Serial No. 737,447.

This invention relates to improvements in mechanism for positioning an interposed ink-ribbon with respect to the printing line of a typewriting machine, and relatively to the 5 main or vibratory ink-ribbon.

There is provided a simple, inexpensive and highly efficient controlling device for the auxiliary ink-ribbon. Certain features herein shown are described in my co-pending 10 application filed July 25, 1924, Serial No. 728,073 (now Patent No. 1,624,697, dated April 12, 1927). The means described in said 15 application is directed towards locating a stretch of the auxiliary ribbon so that when it is not positioned at the printing line it is located above the printing line; the stretch of auxiliary ink-ribbon being arranged in two 20 portions, both horizontal but spaced apart vertically, one portion being located at the printing line, and the other portion thereabove.

It is intended by the present invention to improve upon the means for offsetting the interposed or auxiliary ribbon, so that, the 25 offsetting of the ribbon is accomplished by devices at the end of the carriage, and does not necessitate movement of the hand of the operator longitudinally of the platen.

Another feature of the present invention 30 is the provision of means for simultaneously actuating the mechanism for line-spacing the platen and also the auxiliary ink-ribbon, the offsetting of which latter occurs through the agency of a guide-plate which is shiftable to 35 dispose the two portions of the ribbon in the manner hereinbefore described.

A further feature of this invention is the provision of means, controlled by the operation of the line-spacing mechanism, for shifting the auxiliary ribbon from the printing line to a position away therefrom. However, should it be desired to permanently retain the auxiliary ink-ribbon in ineffective position so 40 as to employ only the main ink-ribbon to produce typed impressions upon the work-sheet, it can be done without operating the means 45 actuating the guide-plate. On the other hand, it may be found desirable to retain this auxiliary ink-ribbon at the printing line for 50 conjoint use with the main ink-ribbon, so as to print upon two work-sheets, line by line, without interruption; in this event the operating handle is latched automatically after

being moved to shift the auxiliary ribbon to locate it at the printing line. Thereupon, 55 the typist positions a detent mounted upon the latch in ineffective position to be engaged by the spacer-slide of the line-spacing mechanism at any time through the operation of the latter. As a result, the latch is not disengaged from the handle by means of the spacer-slide, as is contemplated where the work-sheets take the form of a check and record sheet respectively, so that the handle is still held in operative position and the auxiliary ink-ribbon is still retained at the printing line. When the latch is released automatically by the line-spacer-slide, the operating handle is automatically restored to normal position by means of a spring, and this 60 action, through suitable connections, will cause the auxiliary ink-ribbon to return to ineffective position.

Owing to the co-action between the line-spacing of the work-sheets and the shifting 75 of the auxiliary ink-ribbon to ineffective position, it becomes necessary to provide for progressively removing one check and inserting another check upon the upper shelf and in engagement with the platen, because some 80 of the lines typed upon each check will be duplicated through the auxiliary ink-ribbon upon the permanent record-sheet, while other lines need only be typed by means of the main ink-ribbon alone upon the check only. In 85 removing the check it is desired to hold the record-sheet against movement or creeping relatively to the platen, but this would be impossible owing to the casting-off of the feed-rolls holding the check and record-sheet on 90 the platen, were it not for the fact that another set of pressure rolls are provided to clamp down under tension the work-sheet at the top of the platen. In order to permit the record-sheet to be replaced after casting-off 95 the usual feed-rolls, it is also necessary to disengage the pressure-rolls, which press this sheet onto the top of the platen. Manually-controlled mechanism is provided for doing this, which mechanism is controlled by a handle and serves to lift these pressure-rolls out 100 of contact with the platen, thus providing clearance for the removal of the record-sheet.

At the same time this action of casting-off the auxiliary pressure-rolls takes place, the 105 guide-plate, which serves to shift the aux-

iliary ribbon towards and from the printing line, is pushed away from the platen, so as to provide clearance at this point, and so as to facilitate the insertion or removal of a record-sheet.

Another feature of the present invention is the provision of means for causing the usual ribbon-spools, which feed the auxiliary ink-ribbon along the printing line, to be intermittently rotated, this rotation being automatically controlled by the operating handle which controls the operation of the ribbon-shifting guide-plate. However, means are provided for rendering said operating handle ineffective to actuate the ribbon-spools.

A multiplying mechanism controlled by said handle includes multiple gearing between the operating handle and the guide-plate, thus causing this guide-plate to travel a comparatively long distance when a relatively short movement is imparted to the operating handle.

It will be understood, that the present invention is particularly designed for use in connection with typewriting upon the check in a manner where it is intended to type a number of lines on this check and to transfer certain of these lines onto a permanent record-sheet. This record-sheet receives seriatim certain data being usually the name of a person and the amount of the check drawn in favor of this person, the idea being to type upon this record-sheet the aggregate number of amounts drawn upon in favor of different payees listed on different checks. But inasmuch, as each check is typed upon at other points which produces data, which it is not desired to transfer onto the record-sheet, it becomes necessary to prevent the record-sheets from being typed upon during the action of the type-bars against the main ink-ribbon, hence the present invention has been brought about to provide for this occurrence in typewriting practice.

Other features and advantages will herein-after appear.

In the accompanying drawings,

Figure 1 is a vertical transverse elevation, partly in section, of a machine embodying the present invention.

Figure 2 is a fragmentary front elevation thereof.

Figure 3 is a detail sectional view showing means for unseating the auxiliary pressure rolls as well as the aligning guide-plate support.

Figure 4 is a fragmentary top plan view showing the details of construction of the ribbon-spool actuating means.

Figure 5 is a cross sectional elevation of a ribbon-spool.

Figure 6 is a front elevation of the machine showing the auxiliary ink-ribbon located at the printing line.

Figure 7 is a view similar to Figure 6 but

showing the auxiliary ink-ribbon located above the printing line.

Figure 8 is a detail view of the means for unseating the auxiliary pressure rolls.

Figures 9 and 10 are views partly in section showing the latch-bar in inoperative and operative position, respectively, and associated parts.

In the drawings which are merely illustrative of the present invention 10 designates the usual type-bars having the type-surfaces 11 which are caused to impinge upon the main ink-ribbon 12. The usual feed-rolls 13 and 14 apply tension against the under side of the platen 15 mounted on the shaft 16 which is rotatable by the finger-knobs 17. This platen 15 overlies the apron 18 of the usual paper-shelf 19 suitably secured to the end supports 20 of the platen frame, a ratchet-wheel 21 being operatively connected to the shaft 16 for line-spacing the platen. End plates 22 are engaged upon the supports 20.

Guide-members 23 are located fixedly adjacent the opposite ends of the platen and have oppositely-inclined diagonal slots 24 in which are movably guided an auxiliary ink-ribbon 25 which is guided over rollers 26 mounted upon the guide-members 23, the latter serving to divert the horizontal movement of the auxiliary ribbon 25 to a vertical movement, which last-named movement is impressed upon its stretches 29^b and 29^c, the guide-members 23 being secured by brackets 30 upon the supports 20.

Ribbon-spools 31 are positioned at the rear of the guide-members 23 and in line therewith over which the ribbon stretches 20^b and 29^c are trained after leaving the rollers 26. A supporting bar 32 extends longitudinally in front of the platen above the printing line and terminates in right-angularly disposed arms 34, shown in Figure 3, which are fulcrumed so as to pivotally support the reduced ends 33 of said bar, as shown in Figure 6.

The arms 34 have depending lugs 35 held by the springs 36 secured upon the pins 37 mounted in the brackets 30. Secured longitudinally in back of the bar 32 is a rail, track or strip 38 which has its opposite ends 39 secured by fasteners 44 to the bar 32. A ratchet-wheel 40 is secured upon each ribbon-spool 31 for the purpose of rotating the same, each spool being journaled upon a shaft 41 mounted in a bracket 30^a (Figure 5), a suitable spring-brake 42 surrounding the shaft 41 and applying pressure against the side of the spool induced by the thumb screw 43.

Suitable line-spacing mechanism, well known to those skilled in the art, is provided for engaging the ratchet-wheel 21 of the platen shaft 16 for the purpose of rotating the platen 15 and includes the usual line-spacer slide 45. Arranged to slidably engage the track 38 is a sleeve or collar 46 which is formed integrally with a guide-plate 47 hav-

ing vertically-spaced slots 48 and 49 inclining in the same direction and movably guiding the vertical stretch 29 of the auxiliary ribbon 25, this guide-plate slidably engaging the auxiliary ribbon and by reason of the pitch of the diagonal slots serving to offset in zig-zag fashion the auxiliary ribbon 25 to provide operatively-extending horizontally-disposed stretches 27 and 28 which are vertically spaced apart so as to position one stretch at the printing line and the other stretch one line above the printing line.

It will be seen that the guide-plate may occupy an extreme right or left position on the carriage. If it is located at the extreme left end of the platen, as shown in Figure 7, the auxiliary ink-ribbon will extend practically the entire length of the platen above the printing line indicated at E on the check B in Figure 7. Should it be located at the extreme right of the platen the effect will be to position the auxiliary ribbon longitudinally of the platen directly at the printing line, as shown in Figure 6.

25 A pawl 50 is mounted on the pivot pin 51 carried by a lever 52 having a handle 53, the pin being supported upon a lever 54, the free end of which is offset at 54^a and projects in the path of movement of an operating handle 75 about to be described. This lever 54 is fulcrumed on a screw 55 threaded into the bracket 56, a spring 56 secured to a pin 62 serving to hold the lever 54 against the pin 62 to position the free end of the lever 35 54 relatively to the operating handle 75; another spring 57 is secured relatively to a pin 58 on the lever 54 and on the pin 59 on the pawl 50 and exerts a pull that tends to maintain this pawl in engagement with the 40 ratchet-wheel 40.

45 The collar or sleeve 46 of the guide-plate 47 is provided with a stud 64 to which is secured the opposite ends of a cable or belt 65 which is trained upon pulleys or drums 67 and 68, the pulley 68 being fixed upon a stud shaft 69 mounted upon the standard 77 secured to the platen frame, while a journal for the pulley 67 is mounted upon a bracket arm 111 at the right end of the machine. A 50 pinion 70 is fixed upon the shaft 69 for driving the pulley 68 and this pinion meshes with a gear 71 journaled at 72 upon the standard 77. Fast upon the shaft 72 so as to rotate with the latter is a smaller gear 73 which meshes with a sector gear 74 formed with an operating lever 75 having the handle 75^a. A pin 78 is fixedly secured upon the standard 77 which serves to provide a stop for the operating handle lever 75. A suitable spring 115 is secured at one end upon the standard 77 and is secured at its opposite end upon the sector gear 74 and serves to thus normally press the operating handle lever 75 against the stop pin 78.

65 The lever 75 is constrained to travel in the

path of movement of a latch bar 81 fulcrumed upon a screw 85 threaded into the bracket 30 and having a latch hook 80 provided with the finger-piece 82 by means of which it may be retracted. A spring 83 is secured 70 to the latch bar 81 in order to hold the latter pressed with its shoulder 83^a against the stop pin 90, at which time it will be seen that the latch bar 81 inclines in operative position effective to latch the handle lever 75 after 75 the latter has been caused to snap thereunder. A pin 91^a is mounted upon the end of a flat detent spring 81^a, secured to the face of the latch bar 81, and extends through a hole 91 in bar 81. An arm or detent 86 is fulcrumed upon the screw 85 and a pin 87 serves, when the arm or detent has been moved down upon its screw 85, to engage the notch or recess 89 formed upon the lower end of the latch bar 81, below the screw 85, and, in this manner, the pin 87 is limited in movement in the notch, and the terminal lip 88 of the detent is positioned so as to project forwardly to position for actuation by the slide 45.

20 The arm or detent 86 is provided for the purpose of actuating the latch bar 81 to retracted position relatively to the operating handle lever 75 and may be raised out of the path of the slide 45. When in such inoperative position the pin 91^a snaps into a recess 84 in the detent 86.

25 For the purpose of permitting the record-sheet A to be held in proper undisturbed relationship upon the platen 15 while the feed rolls 13 and 14 are being cast-off to release 100 the check B from engagement with the platen, auxiliary pressure rolls are provided to press the record-sheet down upon the upper surface of the platen. Upon a pivot pin 95, located as shown in Figure 3, is fulcrumed a lever 96 105 having an operating handle 97. This lever 96 is formed with a recess 98 between its ends and arranged to be received and held in this recess is a shaft 99 which extends longitudinally of the platen and is supported operatively upon a longitudinally extending series of separated lever arms 100 which are fulcrumed upon a rod or shaft 102, as shown in Figure 3. The pressure rolls 101 are rotatably supported upon the shaft 99. 110 Springs 103 serve to draw downwardly the arms 100 to assure that all the pressure rolls 101 will bear down with sufficient tension upon the top of the platen so as to engage and overlie the record-sheet A.

30 The springs 103 are secured upon the pins 104 secured upon the platen frame and also upon the pins 105 secured directly upon the arms 100. The lever 96 is also formed with a cam 106 in a plane with the recess 98, this cam being normally located so as to extend just beneath the shaft 99. Adjacent the cam and in alignment therewith is the bar 32 which supports the guide-plate 47. 110 designates the usual stop which is secured at 130

any desirable point along the length of the bar 32 to position the adjacent longitudinal edge of the work-sheets thereat. As shown in Figure 6, this stop or rest 110 is located so as to position the work-sheets and especially the removable check B at a point where it is spaced from the adjacent end of the platen. However, it could be located at a point where it would be in vertical alignment with the guide-plate when the latter is located in the extreme left end of the platen, as shown clearly in Figure 7. In this latter position, it will be seen that the check will be permitted to extend with its left edge overlying the guide-plate 47, and the distance of traverse allowed the guide-plate 47 towards the right end of the platen will be regulated so that it will come to rest with the right edge of the check overlying it. The reason for doing this is to avoid collision of the auxiliary ribbon-guide with the side edges of the check which may occur by shifting the ribbon-guide from a position beyond the edge of the check to render the auxiliary ribbon ineffective. The bracket arm 111 supporting the pulley 67 is secured by the plate 112 upon the end support 20, the fasteners 113 holding this plate in position.

The operation of the present invention will now be detailed. The typist first of all inserts the record-sheet A in position to engage the platen. A check B is next inserted in position so as to be interleaved between the main ink-ribbon 12 and the auxiliary ink-ribbon 25; it is proposed to type upon the check line C to write in the name of the payee of the check as well as the amount to be paid him; and also in the next succeeding line D to write in, unabbreviated, the full amount of the check opposite the printed legend "Dollars". Of course for permanent record purposes it would be mere repetition to reproduce both lines C and D upon the record sheet, therefore it is intended only to transfer line C of each check upon the record-sheet so that the latter will contain a permanent record seriatim of all the payees of the several checks successively typed upon together with the amounts drawn upon against the payors of these checks in favor of the payees. It becomes necessary to position the auxiliary ink-ribbon directly at the printing line of the machine to make it align with the main ink-ribbon in order to assure that when line C is typed upon the check through the medium of the main ink-ribbon the typed impressions thus produced will be simultaneously reproduced or transferred through the auxiliary ink-ribbon upon the record-sheet A.

When the parts of the present device are in normal position the guide-plate will be located at the extreme left end of the platen. In order to position the auxiliary ink-ribbon at the printing line, it must be moved downwardly as it is disposed just one line above

the printing line, but still in the printing zone when the guide-plate 47 occupies the extreme left end position shown in Figure 7. The typist grasps hold of the operating handle 75 and pulls the same downwardly until the handle rides over the wedge-shaped hook 80 of the latch-bar 81 and then it forces this latch-bar backwardly and snaps under said hook, so as to be latched by the bar and held stationary in a horizontal position shown in Figure 6. However, the operating handle 75 before engaging the latch-bar engages the lever 54 and forces the same downwardly against the tension of the spring 61, and as the lever 54 moves downwardly so does the pawl 50 which thus actuates the ratchet-wheel 40, thus rotating the spools 31 and feeding along the auxiliary ink-ribbon, so that a fresh surface of this ribbon will be advanced longitudinally of the printing line.

As the operating handle 75, has moved downwardly to latched position, the sector-gear 74 turns and rotates the small gear or pinion 73 which also rotates the larger gear 71 which meshes with the small gear or pinion 70, thereby rotating the pulley or sheave 68, thus setting in motion the cable 65 and drawing along the lower stretch thereof in a direction toward the right end of the machine, and as this stretch is secured to the stud 64 of the guide-plate 47 the latter is caused to move away from its normal position at the left of the machine, and because of the gear multiplying power one actuation of the operating handle 75 serves to turn the gears a sufficient distance to project the guide-plate 47 the distance shown in Figure 6 where it comes to rest at a point where the right edge of the check B will overlie it at its median line. The ribbon is now at the printing line.

Where, as in Figure 6, the stop 110 is located at a point spaced in advance of the position occupied by the guide-plate 47 when in the normal position shown in Figure 7, the manner of inserting the check in proper relationship with the platen will be as follows:— In order to avoid spoiling the edge of the check by the forcible contact made therewith by the guide-plate edge in the act of the latter beginning its traverse toward the right end of the platen, the check need not be inserted until after the guide-plate has been moved to its qualified position shown in Figure 6, when the auxiliary ink-ribbon has been located at the printing line. The stop 110 might, however, advantageously be positioned at a point where it will lie midway the width of the guide-plate, thus, making it certain that, when it begins its movement as well as ends its traverse, the guide-plate will not engage either edge of the check.

The first line of the check is now typed as indicated in Figures 6 and 7 which will be also simultaneously typed upon the record-sheet; the next line need not be reproduced

upon the record-sheet so this time the line-spacing mechanism is operated by turning the lever (not shown) upon its pivot which actuates the sliding of the slide 45, so that, 5 as soon as the platen is turned by this mechanism for the purpose of line-spacing the check and record-sheet, the slide 45 moves and collides with the detent or lever 86, and as it pushes the forwardly projecting end of 10 the lip 88 of this detent, the pin 87 on this detent forces back the lower end of the latch-bar 81 with the result that the latch-bar is tilted or rocked by the tripping action of the slide thereby causing its upper hook 80 to 15 be disengaged and released from holding engagement with the handle 75 which being free is urged back to normal position under influence of the spring 115 and as it thus is thrust back to its normal upright position 20 the gearing is again operated. The pulleys 67 and 68 turn and the cable 65 shifts the guide-plate 47 from the right end position to the left so that the auxiliary ink-ribbon 25 is pulled upwardly one line above the 25 printing line. When now the second line is typed upon the check, the main ink-ribbon 12 alone will be presented against the type-bars so that the auxiliary ribbon will not 30 serve to transfer the typed impressions made on the check onto the permanent record-sheet A. Figure 7 illustrates the fact that only the check will be typed upon to produce the second typed line as it appears that the auxiliary ribbon 25 is spaced above the printing line. It also appears from a comparison 35 made with Figure 6 that both the check and the work-sheet A have been line spaced at the same time to assure that the same line will not be typed upon again; that the auxiliary ink-ribbon 25 has at the same time been pulled upwardly so as to allow the type-bars 40 to print only upon the check.

The check may now be removed and another check inserted to be typed upon in a 45 manner already described. Before removing the check it must be ascertained whether the record-sheet A is to be removed also, which need be done only if the last line has 50 been typed thereupon at the bottom of this sheet. Should the record-sheet remain in the machine, the check is removed while the auxiliary pressure rolls engage the record-sheet at the upper end of the platen, as illustrated in Figure 3, so that while the usual feed-rolls 55 13 and 14 are cast off, the auxiliary pressure rolls still hold the record-sheet onto the platen without disturbing its relative position with respect to the next and each succeeding check to be placed thereagainst on 60 the platen. But the moment when the record-sheet is to be removed with the check it is necessary to operate the handle 97 to force the lever arm 96 forwardly. When this is 65 done, the cam 106 on the lever 96 rides against the rod 99, thereby lifting it and

raising the pressure rollers 101 out of contact and engagement with the upper part of the platen. At the same time the cam is acting to lift the rod 99, it is being urged in the direction of the aligning bar 32, and it is 70 designed that at the moment that this cam engages this bar to swing it outwardly of the platen to provide clearance between the guide-plate 47 and the platen, the recess 98 of the lever 96 will come immediately under the shaft or rod 99 and the springs 103 will thereupon draw the rod 99 into this recess thereby latching the rod and separating the series of rollers 101 from contact with the platen and providing clearance between 75 these rollers and the platen at this point. The record-sheet and check may now be quickly removed from the platen after casting off the feed-rollers 101. This is illustrated in Figure 8. It will be seen that when 80 the lever 96 is shifted rearwardly it will temporarily be unlatched from the rod 99 allowing the cam 106 to again engage the rod 99 and as the lever 96 recedes the rod is allowed to come down until the rollers 101 again engage the platen to hold the new record-sheet 85 and check.

Should it be desired to permanently make carbon or duplicate copies on the record sheet of all the matter typed upon one work-sheet (which may be check, bill, etc.), it is necessary then to retain the auxiliary ink-ribbon at the printing line. In order not to shift the auxiliary ink-ribbon away from the printing line each time the line-spacing mechanism is operated to rotate the platen for line-spacing purposes, the typist will take hold of the detent 86 and lift the same upwardly to the position shown in Figure 10 and will laterally strain this detent to allow 100 its pin 84 to enter the hole 91 formed upon the latch-bar 81 so that the detent will thus be releasably held in ineffective position; so that whenever the line-spacer slide 45 makes its forward thrust it will not collide with the 105 trip detent 86. The latch-bar 81 will thus be ineffective to unlatch the operating handle 75; in this way the position of the auxiliary ink-ribbon at the printing line will not be disturbed.

It may also be desirable to retain the auxiliary ink-ribbon in ineffective position one line above the printing line. In this event the guide-plate will remain stationary at the left end of the platen, as shown in Figure 7. The typist will not actuate the operating handle 75. The guide-plate supports the auxiliary ink-ribbon between its ends, so that should the platen be rotated reversely to retract the work-sheets or for any other reason, 120 it is assured that the auxiliary ink-ribbon will not be carried along with the platen and thus be injured.

From the foregoing, it will be seen that a simple and inexpensive contrivance for shift- 125 130

ing the auxiliary ink-ribbon is obtained by the parts illustrated in the drawings by which the action of positioning the auxiliary ink-ribbon at the printing line is manually controlled, so that the typist can reproduce at will, on a record sheet, any of the lines typed upon the check. It will be further seen that the restoration of the ribbon to ineffective position is rendered automatic, so as not to require any attention on the part of the typist, this action being controlled through and by the line-spacing mechanism, and that auxiliary pressure-rollers are provided for assisting in maintaining the work-sheets in contact with the platen singly or collectively as well as to allow for singly or collectively removing them from engagement with the platen.

Variations may be resorted to within the scope of the invention, and portions of the improvements may be used without others.

Having thus described my invention, I claim:

1. In a typewriting machine, the combination of a platen, an auxiliary ink-ribbon extending therewith and traveling therewith, a ribbon-guide movable lengthwise of the platen, the guide being effective, when moved in one direction, to dispose said ribbon along the platen at the printing line, and effective, when moved in the opposite direction, to displace said ribbon therefrom, an operating handle adjacent one end of the platen, and connections between the handle and the guide, whereby said handle may move the guide in either direction along the platen, to determine the position of said ribbon relatively to the printing line.

2. In a typewriting machine, the combination of a platen, an auxiliary ink-ribbon extending lengthwise thereof and traveling therewith, a ribbon-guide movable along the platen, the guide being effective, when moved in one direction, to dispose said ribbon along the platen at the printing line, and effective, when moved in the opposite direction, to displace said ribbon therefrom, an operating handle adjacent one end of the platen, gearing associated with the handle, and connections between said gearing and the guide, whereby the handle moves said guide in either direction along the platen, to determine the position of the ribbon relatively to the printing line.

3. In a typewriting machine, the combination of a rotatable platen, an auxiliary ink-ribbon extending therewith and traveling therewith, a ribbon-guide movable along the platen, the guide being effective, when moved in one direction, to dispose said ribbon along the platen at the printing line, and effective, when moved in the opposite direction, to displace said ribbon therefrom, an operating handle adjacent one end of the platen, multiplying gearing associated with the handle, and connections between the gearing and the

guide, whereby said gearing causes a relatively long travel of said guide upon actuation of the handle.

4. In a typewriting machine, the combination of a platen, an auxiliary ink-ribbon extending therewith and traveling therewith, a ribbon-guide movable along the platen, the guide being effective, when moved in one direction, to dispose the ribbon along the platen at the printing line, and effective, when moved in the opposite direction, to displace said ribbon therefrom, an operating handle adjacent one end of the platen, gearing associated with said handle, pulleys arranged at the opposite ends of said platen, said gearing 75 rotating one of said pulleys, and a belt carried upon said pulleys and attached to the guide for moving the same along the platen upon actuation of the handle.

5. In a typewriting machine, the combination of a rotatable platen, an auxiliary ink-ribbon extending along said platen and traveling therewith, a track arranged lengthwise adjacent the platen, a ribbon-guide slideable on said track, the guide being effective, 90 when moved in one direction, to dispose the ribbon along the printing line, and effective, when moved in the opposite direction, to displace said ribbon therefrom, an operating handle adjacent one end of the platen, and connections between the guide and the handle, whereby the latter effects a traverse of said guide in either direction along the track, to determine the position of the ribbon relatively to the printing line.

6. In a typewriting machine, the combination of a rotatable platen, an auxiliary ink-ribbon extending along the platen and traveling therewith, a ribbon-guide movable along the platen, the guide being effective, when moved in one direction, to dispose the ribbon along the printing line, and effective, when moved in the opposite direction, to displace said ribbon therefrom, an operating handle, connections between the operating handle and the guide, a releasable latch for holding the handle in position for disposing the ribbon along the printing line, and means rendering said handle effective to displace the ribbon from the printing line upon release of 105 said latch.

7. In a typewriting machine, the combination of a platen, an auxiliary ink-ribbon extending along the platen and traveling therewith, ribbon-spools for the ink-ribbon, a movable ribbon-guide through which the ribbon is threaded, the guide being movable in one direction along the platen for disposing said ribbon along the printing line and movable in a counter-direction to shift it away from the printing line, an operating handle, connections between the handle and the guide, the handle being effective to move the guide in either direction, to determine the position of the ribbon, and means associated with said 125 130

ribbon-spools and driven by the handle, whereby said handle causes the ribbon to feed along the platen during an actuation of said handle to move the guide.

5 8. In a typewriting machine, the combination of a platen-frame, a platen mounted therein, line-spacing mechanism, an auxiliary ink-ribbon extending along the platen and traveling therewith, a ribbon-guide movable 10 along the platen, the guide being effective, when moved in one direction, to dispose the ribbon along the printing line, and effective, when moved in the opposite direction, to displace said ribbon therefrom, an operating 15 handle, connections between the operating handle and the guide, a releasable latch for holding the handle in position for disposing the ribbon along the platen at the printing line, means operating to release said latch 20 upon actuation of the line-spacing mechanism, and means rendering said handle effective to displace the ribbon from the printing line after the latch has released the handle.

9. In a typewriting machine, the combination of a platen-frame, a platen mounted therein, line-spacing mechanism, an auxiliary ink-ribbon extending along the platen and traveling therewith, a ribbon-guide movable along the platen, the guide being effective, when moved in one direction, to dispose the ribbon along the printing line, and effective, when moved in the opposite direction, to displace said ribbon therefrom, an operating handle, connections between the operating 30 handle and the guide, a releasable latch for holding the handle in position for disposing the ribbon along the printing line, means operating to release said latch upon actuation of the line-spacing mechanism, means rendering said handle effective to displace the ribbon from the printing line after the latch has released the handle, and ribbon-feeding mechanism actuated by said handle.

10. In a typewriting machine, the combination of a platen-frame, a platen rotatably mounted therein, a displaceable support extending longitudinally adjacent the front of said platen, an ink-ribbon, a ribbon-guide slidably mounted upon said support and effective to locate said ribbon along the printing line or remove the same therefrom, pressure rollers releasably engaging the upper portion of said platen, and a finger-piece for raising said rollers out of contact with said platen 55 and for moving said support away from said platen.

11. In a typewriting machine, the combination of a platen-frame, a platen rotatably mounted therein, an ink-ribbon extending along said platen, a displaceable support extending longitudinally of the platen adjacent the front thereof, and a ribbon-guide slidably on said support and effective, when moved in one direction, to dispose said ribbon along the platen at the printing line,

and effective, when moved in the opposite direction, to displace said ribbon from the printing line, the ribbon being bodily shiftable away from the platen by reason of the displaceability of the ribbon-guide support. 70

12. In a typewriting machine, the combination of a platen-frame, a platen rotatably mounted therein, a ribbon extending longitudinally of said platen, a displaceable support extending longitudinally adjacent the 75 front of the platen, a ribbon-guide slidably mounted upon said support and effective to locate said ribbon along the printing line or remove the same therefrom, pressure rolls releasably engaging the platen, means for 80 yieldingly pressing said support toward the platen, a stop for determining the position of said support when pressed toward the platen, and a finger-piece for releasing said rolls and for moving said support away from 85 the platen to provide a space between the latter and the ribbon.

13. In a typewriting machine, the combination of a platen-frame, a platen revolvably mounted therein, line-spacing mechanism, an auxiliary ink-ribbon extending along the platen and traveling therewith, a ribbon-guide movable along the platen, the guide being effective, when moved in one direction, to dispose the ribbon along the printing line, 90 and effective, when moved in the opposite direction, to displace said ribbon therefrom, a spring-retumed operating handle, driving connections between the handle and the guide, a releasable latch automatically engaging 100 said handle to hold the same in position with the ribbon disposed along the printing line, and means co-operating with the line-spacing mechanism and associated with said latch for releasing the latter upon a line-spacing operation, said means being movable to position 105 whereby to render said line-spacing mechanism ineffective to release said latch.

14. In a typewriting machine, the combination of a rotatable platen, a bar extending 110 in front thereof, a pair of arms supporting said bar and being pivotally supported adjacent the ends of said platen, a rod disposed above said platen, means for movably supporting said rod, a series of rollers journaled 115 on said rod and yieldably engaging said platen, a ribbon extending along said platen, a ribbon-guide carried by said bar, the guide being movable along the platen to dispose said ribbon along the printing line or removed therefrom, a spring causing said bar to hold the guide under tension against the platen, an operating lever swingable adjacent said bar, the lever being formed with a recess, and a cam carried by said lever in 125 advance of said recess and arranged to engage said rod so as to lift said rollers out of engagement with said platen and so as to reach and engage said bar to push the same away from said platen against the tension of 130

the spring, said lever, during its last-named movement, causing said rod to automatically become lodged in said recess whereby said rollers are latched out of engagement with said platen.

15. In a typewriting machine, the combination of a rotatable platen, an auxiliary ribbon extending along the platen and traveling therewith, a ribbon-guide movable along the 10 platen, the guide being effective, when moved in one direction, to dispose the ribbon along the platen at the printing line, and effective, when moved in the opposite direction, to displace said ribbon therefrom, an operating 15 handle adjacent one end of the platen, driving connections between the handle and the guide, a latch-bar pivoted adjacent said operating handle and engaging said handle at the end of the latter's stroke when moving 20 the ribbon to the printing line, a spring yieldably holding said latch in engagement with said handle, means for line-spacing said platen including a spacer slide, a detent carried by said latch-bar and arranged to be lowered 25 so as to project forwardly of said latch-bar and into the path of the spacer slide, whereby said spacer slide releases the handle upon actuation of the line-spacing means against the tension of said spring, and a 30 spring associated with said operating handle and effective upon disengagement of said latch-bar to cause said handle to again actuate said guide, thereby displacing the ribbon from the printing line.
- 35 16. In a typewriting machine, the combination of a revoluble platen, spools arranged adjacent the opposite ends of said platen, an ink-ribbon extending longitudinally along said platen and having its ends wound upon 40 said spools, an operating handle adjacent one of said spools, a ribbon-guide movable by said handle along the platen, the guide being effective, when moved in one direction, to dispose said ribbon along the platen at the printing line, and effective, when moved in the opposite direction, to remove said ribbon from 45 the printing line, and means controlled by said operating handle for rotating one of said spools to feed said ribbon.
- 50 17. In a typewriting machine, the combination of a revoluble platen, line-spacing mechanism including a spacer slide, an auxiliary ink-ribbon extending along the platen, a ribbon-guide movable along the platen, the 55 guide being effective, when moved in one direction, to dispose said ribbon along the platen at the printing line, and effective, when moved in the opposite direction, to displace said ribbon therefrom, a spring-retumed 60 operating handle, driving connections between said handle and the ribbon-guide for moving the same in either direction, a latch-piece automatically engaging around said handle to hold the same in position with said

ribbon disposed along the printing line, the 65 handle being so held against the tension of the return spring, a shiftable detent carried by the latch-piece, a pin carried by the detent, the latch having a notch into which the pin is received, whereby to position said detent in 70 the path of line-spacing travel of the spacer slide, the latter being effective to strike said detent and thereby release the latch from engagement with said handle, and means for retaining said detent in a shifted position 75 away from the path of the spacer slide.

18. In a typewriting machine, the combination of a platen-frame, a revoluble platen, an auxiliary ink-ribbon extending along the 80 platen, a ribbon-guide movable along the platen, the guide being effective, when moved in one direction, to dispose the ribbon along the printing line, and effective, when moved in the opposite direction, to remove said ribbon from the printing line, a latch-bar 85 fulcrumed upon the platen-frame, said latch bar being provided with a hook at one end and having a notch and a shoulder at its opposite end, a detent pivoted upon said latch-bar and including a terminal lip, a pin on said detent engageable with said notch to cause said lip to project forwardly of said shoulder, a stop-pin against which said shoulder rests for determining the latched position of said latch-bar, an operating 90 handle, gearing driven by the handle, connections between the gearing and the ribbon-guide for moving the same in either direction by means of the handle, a spring engaging said latch-bar to hold its shoulder 95 against said stop-pin and to position said hook in the path of movement of said handle, said handle in its movement in one direction snapping under said hook, line-spacing mechanism including a spacer slide arranged to 100 collide with said lip to force the hook of said latch-bar out of engagement with said handle, and a spring associated with said handle for thereafter throwing the same to position whereby to remove said ribbon from 105 the printing line.

19. In a typewriting machine, the combination of a platen-frame, a platen rotatably mounted therein, a standard on one end of said frame, a sector-gear pivoted on said standard, a pintle adjacent said sector-gear, a shaft on said standard, a pinion on said shaft, a pinion on said pintle and meshing with the shaft-carried pinion, a pinion fixed coaxially upon said pintle-carried pinion 115 and meshing with the sector-gear, a pulley secured to said shaft, a pulley at the opposite end of said frame, a cable carried upon said pulleys, an auxiliary ribbon stretched along the platen, a ribbon-guide movable along 120 said platen, the guide being effective, when moved in one direction, to dispose said ribbon along the printing line, and effective when 125

- 5 moved in the opposite direction, to displace said ribbon from the printing line, the cable being connected to the guide, and a handle for imparting motion to the sector-gear, whereby to move said guide along the platen.
- 10 20. In a typewriting machine, the combination of a rotatable platen, line-spacing mechanism, an auxiliary ink-ribbon extending along the platen, a ribbon-guide movable to dispose the ribbon in a position along the platen at the printing line or to a position above the printing line, a handle carrying lever mounted adjacent one end of the platen, driving connections between the lever and the guide, including gearing, a releasable latch for holding the handle in position with said ribbon disposed along the printing line, said line-spacing mechanism being effective to release the lever, and a spring for there-20 after moving the lever to move the ribbon to said position above the printing line.
- 15 21. In a typewriting machine, the combination of a revoluble platen around which a pair of work-pieces are fed to typing position, line-spacing mechanism, a displaceable ink-ribbon interleaved with said work pieces, a ribbon-controlling guide for the ribbon, the guide being movable along the platen to locate said ribbon at the printing line or in 30 a position displaced therefrom, and means for causing said guide to automatically return said ribbon from position along the printing line, to position displaced therefrom upon a line-spacing actuation of the platen.
- 25 22. In a typewriting machine, the combination of a revoluble platen, an auxiliary ink-ribbon interleaved between work-sheets fed around the platen, a ribbon-guide for causing said ribbon to be moved to position downward or upward relatively to the printing line, a manual actuator for said guide, a spring-pressed latch under which said actuator snaps so as to hold said guide with the ribbon stationary at the printing line, line-spacing mechanism for said platen, and 40 means operated by said mechanism for tripping the latch out of engagement with said actuator, said guide, upon the tripping of said latch, automatically moving said ribbon away from the printing line.
- 45 50 23. In a typewriting machine, the combination of a carriage, a revoluble platen in said carriage, an auxiliary ribbon on said carriage extending lengthwise of said platen, a ribbon-guide movable along the platen, the 55 guide being effective, when moved in one direction, to dispose the ribbon along the printing line, and effective, when moved in the opposite direction, to displace said ribbon therefrom, platen line-spacing mechanism, and means under the control of the line-spacing mechanism and associated with
- 5 said guide for effecting a shifting thereof to displace the ribbon from the printing line.
- 60 24. In a typewriting machine, the combination of a carriage, a platen on said carriage, type-bars to print at a common point against said platen, a ribbon extending lengthwise of the platen, a ribbon-guide, platen-line-spacing mechanism, and means under the control of the line-spacing mech-65 anism to shift the ribbon-guide whereby to move the ribbon from the printing point to an ineffective position at one side thereof.
- 65 70 25. In a typewriting machine, the combination of a carriage, a platen on said carriage, line-spacing mechanism, a ribbon extending along the platen and traveling therewith, a shiftable ribbon-controlling guide on said carriage and movable therealong, a portion of the ribbon extending from one side 75 of said guide along said platen to cover the printing line, and a portion of the ribbon extending from the other side of said guide along the platen to one side of the printing line, means including a handle at one end of the carriage for imparting motion to said guide, releasable means for holding the handle in one position, said releasable means being operatively associated with the line-spacing mechanism, and a spring for moving 80 said handle to another position upon release.
- 75 80 26. In a typewriting machine, the combination with a carriage having a platen thereon and type-bars to print at a common point against the latter, of a ribbon disposed along said platen, a movable ribbon-guide, 85 line-space mechanism associated with said platen, means rendered effective by the actuation of the line-space mechanism to move the ribbon-guide whereby to shift said ribbon from said printing point to an ineffective position adjacent the same, and means to move said ribbon-guide independently of said line-space mechanism, whereby to shift said ribbon from said ineffective position to the printing point.
- 90 95 27. In a typewriting machine, the combination with a carriage having a platen thereon and type-bars to print at a common point against the latter, of a ribbon disposed along said platen, a movable ribbon-guide, 100 line-space mechanism associated with said platen, and means rendered effective by the actuation of the line-space mechanism to move the ribbon-guide whereby to shift said ribbon from said printing point to an ineffective position adjacent the same, said means being independently operable to move said ribbon-guide, whereby to shift said ribbon from said ineffective position to said printing point.
- 105 110 115 120

JOHN WALDHEIM.
